UNITED STATES PATENT OFFICE.

THOMAS SCOTT HERRICK, OF MUNCIE, AND JOHN H. BISSETT AND FRANZ M. MERRICK, OF ANDERSON, INDIANA, ASSIGNORS, BY DIRECT AND MESNE ASSIGNMENTS, TO JOHN C. GRIESHEIMER, EDWARD TUHEY, AND THOMAS SCOTT HERRICK, OF MUNCIE, INDIANA.

TROLLEY-WIRE FINDER.

SPECIFICATION forming part of Letters Patent No. 726,917, dated May 5, 1903.

Application filed August 23, 1902. Serial No. 120,769. (No model.)

To all whom it may concern:

Be it known that we, THOMAS SCOTT HERRICK, of Muncie, county of Delaware, and JOHN H. BISSETT and FRANZ M. MERRICK, of Anderson, county of Madison, and State of Indiana, all citizens of the United States, have invented a certain new and useful Trolley-Wire Finder, of which the following is a specification.

10 The object of the invention is to construct a device of this character that will in the event of the trolley-wheel jumping the wire find the wire and guide the same to means which elevates the wire and throws it upon the trolley-wheel automatically; and with this and minor objects our invention consists of the parts and combination of parts, as will hereinafter be more fully set forth. These and other objects not hereinbefore mentioned 15 are accomplished by the construction illustrated in the accompanying drawings, wherein like letters of reference indicate corresponding parts in the several views, and in which—

20 Figure 1 is a side elevation of the upper portion of a trolley-pole and the trolley-head and trolley-wheel and our improved finder applied thereto. Fig. 2 is a section on the line 2 2. Fig. 3 is a top plan view of Fig. 1. Fig. 4 is a top plan view similar to Fig. 3, 25 showing the position of the guide-wheel reversed.

In the drawings, 1 designates the upper end of a trolley-pole of approved construction, 30 and 2 the head, secured to the upper end of the pole in any suitable manner. Rigidly secured to the upper end of the head is the axle 3. This axle can be secured in place by means of the pin 4. Journaled centrally on this axle 35 is the trolley-wheel 5. Journaled on the axle and on opposite sides of the trolley-wheel are two right and left hand spirally-grooved rollers numbered 6 and 7, respectively. Interposed between the inner ends of the spirals 40 and the sides of the trolley-wheel are guide and lifting wheels 8. These guide and lifting wheels 8 are mounted eccentrically on the

axle 3, so that when not in use will hang down below the periphery of the trolley-wheel, thereby being entirely out of the way, as 50 shown in Fig. 2. Each guide-wheel is provided with a groove 9 in its periphery extending nearly around the same, in which is secured a rubber or other frictional tread 10. The balance of the periphery is cut away on 55 an angle, as shown at 11, Fig. 4, said cut-away or cam portion extending from one edge of the wheel to the other, the angle of the cut-away portion being formed on the same angle as angle of the groove in the trolley-wheel 5. The guide-wheel 8 is provided with spokes 12 and 13, the spoke 13 being cut out on an angle to agree with the cut-away portion 11. The spirally-grooved wheels and the guide-wheels are formed integral. 60

The operation is as follows: If the wire leaves the trolley-wheel, it will be found and screwed into the groove of the guide-wheel. The revolving will lift the wire up above the groove in the trolley-wheel. By that time the 70 wire will have left the groove in the guide-wheel and will engage the cam or cut-away portion of the same. This cam or cut-away portion will now force the wire over directly above the groove in the trolley and the wire 75 will fall into the groove, and the guide-wheel by its weight will further revolve and assume the position shown in Fig. 2 and be entirely out of the way until the wire should again leave the trolley-wheel, when the operation 80 will be repeated.

To make sure that there will always be an electrical contact between the grooved wheels and the head, we provide conductors 14, which are secured to the arms of the head. These 85 conductors have their upper ends free, as shown at 14, and surround the axle. Their upper ends being free, they will have a spring action and always bear against the outer ends of the grooved wheels. In lifting the wire on 90 the guide-wheel there will always be sufficient wire bearing against the side of the groove, so as not to break the current.

We are aware that many minor changes

can be made in the construction and arrangement of parts without in the least departing from the nature and principles of our invention.

5 What we claim as new, and desire to secure by Letters Patent, is—

In a trolley-wire finder, the combination with a trolley-wheel, of a finding device for the trolley-wire consisting of a spiral-groove 10 roller and a guide and lifting wheel eccentrically secured thereto, the guide-wheel having a groove extending nearly around its periphery and a cam on its periphery between the ends of the grooves, the spiral-groove

roller being adapted to find and guide the wire 15 when it leaves the trolley-wheel to the lifting-wheel and the lifting-wheel being adapted to lift the wire from the roller into the groove in the trolley-wheel.

In testimony whereof we have hereunto affixed our signatures in the presence of two witnesses.

THOMAS SCOTT HERRICK.

JOHN H. BISSETT.

FRANZ M. MERRICK
